Primary Examiner — Richard E Chilcot

(57) **CLAIM**

The ornamental design for an eyelet, as shown and described.

DESCRIPTION

1. Eyelet

1.1: Perspective view;

1.2: Side view;

1.3: Top view;

1.4: Bottom view

1.5: Another side view; and

1.6: Cross-sectional view along line A-A.

The letters ("A") and the arrows in reproduction 1.3 are only to show a part of cross section and form no part of the claimed design.
